UNITED STATES PATENT OFFICE

FREDERICK ERNEST OSBORNE, OF STRATFORD-ON-AVON, ENGLAND, ASSIGNOR TO PERMANENT POSTERS (FREDERICK ERNEST OSBORNE, ARCHIBALD JOHN ORR, AND ARTHUR EDWARD NEWSOM THOMAS, PARTNERS), OF LONDON, ENGLAND

ORNAMENTAL PLAQUE AND THE LIKE

Application filed December 4, 1928. Serial No. 323,785, and in Great Britain July 21, 1928.

This invention comprises improvements in or relating to ornamental plaques and the like and is concerned principally with (although not limited to) the production of artistic advertisements.

This invention provides a process for producing an ornamental plaque which consists in preparing a foundation of mouldable material, applying to said foundation a multi-coloured surface, and coating said surface with a transparent or translucent waterproofing material.

In a more specific form the process according to the invention consists in preparing a plaque of plaster or other porous cementitious material, impregnating a surface of the plaque with a pore-filling material, applying to the filled surface a ground coating of impervious material, applying pigments or colouring matter to the ground coating in order to produce the pattern required, and finally covering the patterned surface with cellulose or other waterproofing varnish.

In the accompanying drawing which illustrates one embodiment of my invention,

Figure 1 is a vertical cross-section through a plaque, and

Figure 2 is a plan view.

In one example according to the invention the plaque is manufactured in the following way. The foundation comprises what is known as "fibrous plaster", which material is built up of successive layers of plaster, strips of jute canvas and wooden laths.

The pictorial representation or other design to be displayed is produced in bas-relief and for this purpose a mould is prepared into which is first filled a relatively thin layer of plaster of Paris. Strips of jute canvas or

like material are pressed on to the back of this plaster layer, then further plaster is added after which wooden laths are inserted. Further successive layers of plaster, canvas and wooden laths may be inserted in the

mould until the desired thickness of the plaque has been obtained. After the plaque has been removed from the mould, the surface in relief is impregnated with a pore-filling material such as boiled linseed oil.

The surface is then dried and a ground coat-

ing of impervious material, such as an enamel paint with a white lead base is applied to the filled relief surface. Pigments or other colouring materials are now painted or otherwise applied to the ground coating so as to produce the required pattern, and finally the finished surface is protected by coating it with one or more layers of cellulose varnish, applied preferably by a spraying process.

Instead of applying the colouring matter directly to the ground coating, there may first be applied to this coating gold, silver or other metal in the form of a paint or alternatively as metal foil. The surface so treated is then painted to produce the required multi-coloured surface.

This invention includes an ornamental plaque (particularly intended for advertising purposes) comprising a foundation of plaster or other mouldable material having on it a pictorial representation or the like molded in bas-relief, a multi-coloured surface applied to the foundation (e. g. by painting, spraying or otherwise) and a protective covering for that surface comprising a coating of cellulose varnish or like transparent or translucent waterproofing material.

The products produced by this invention possess considerable artistic merit, and by reason of the final coating of cellulose or like varnish the colouring matter is protected against deterioration under atmospheric influences.

I claim:

1. A method of producing an ornamental plaque which consists in preparing a foundation of moldable cementitious material with the desired pictorial representation molded in bas-relief on one surface of the foundation, impregnating the molded surface with impervious material, and applying a multi-colored coating to said surface cooperating with the bas-relief to complete the pictorial representation.

2. A method of producing an ornamental plaque which consists in preparing a foundation of moldable cementitious material with the desired pictorial representation molded

- in bas-relief on one surface of the foundation, impregnating the molded surface with impervious material, applying metal foil to the impregnating surface, applying a multi-colored coating to at least portions of the surface of the metal foil cooperating with the bas-relief to complete the pictorial representation, and rendering the finished surface water-proof by the application to it of a protective varnish.
- 10 3. An ornamental plaque depicting a pictorial representation comprising a foundation of molded cemeticious material having the desired pictorial representation molded in bas-relief on one surface of the foundation, the surface having the pictorial representation thereon being impregnated with impervious material, a multi-colored coating on said surface which cooperated with the bas-relief to complete the pictorial representation, and a coating of protective waterproof varnish on the multi-colored coating.
- 15 20 In testimony whereof I affix my signature.
